UNITED STATES PATENT OFFICE

108,120

DESIGN FOR A SHOE

Louis J. Epstein, Jersey City, N. J.

Application November 8, 1937, Serial No. 72,688

Term of patent 3½ years

To all whom it may concern:

Be it known that I, Louis J. Epstein, a citizen of the United States of America, residing in Jersey City, county of Hudson, and State of New Jersey, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view thereof.

An essential feature of my design resides in the particular type of woven material of contrasting color constituting the upper portions of the shoe.

I claim:

The ornamental design for a shoe, substantially as shown and described.

LOUIS J. EPSTEIN.
